UNITED STATES PATENT OFFICE.

CHARLES H. TURNER, OF STATESVILLE, NORTH CAROLINA.

THRASHING-MACHINE CONSTRUCTION.

Application filed March 19, 1927. Serial No. 176,731.

This invention relates to a grain thrasher, and has for its primary object the provision of operating mechanism supported in a novel manner by a specially designed frame, the latter not only supporting the mechanism but effectively embracing and resisting all the usual strains to which a grain thrasher is subject in the use thereof.

An object of the invention is to so design 10 the operating mechanism that the same performs the dual function of efficiently operating the various parts and substantially holding the various parts associated and in proper alignment.

15 An object of the invention is the construction of novel operating mechanism in which the various parts are so designed and connected that all bearings are exteriorly arranged to be readily accessible.

20 Another object of the invention is the provision of novel supporting and actuating mechanism whereby the parts actuated and associated therewith may have a more compact arrangement to lower the center of gravity of the machine as a whole.

Besides the above, my invention is distinguished in the substantial manner in which each part is designed and coacts with its associate parts so as to perform its own operation very efficiently and further coacts to 30 materially reinforce the thrasher throughout, thereby greatly prolonging the life of the thrasher.

A feature of my invention is the novel manner of arranging and connecting the various rods so as to assure the proper alignment and correlation of the parts and actuating the same by suitable mechanism exteriorly arranged for inspection at all times.

40 Another feature of my invention is the novel design and association of the component parts that not only assures efficient operation but reduces friction to a minimum.

With these and other objects in view, my 45 invention will be better understood from a description of the same when taken in connection with the accompanying drawings, wherein:—

Figure 1 is a side elevation of a grain 50 thrasher constructed in accordance with my invention;

Figure 2 is a sectional view;

Figure 3 is a horizontal sectional view directly above the straw rack;

Figure 4 is a horizontal sectional view directly above the grain pan;

Figure 5 is a vertical sectional view contiguous to the front mechanism;

Figure 6 is a vertical sectional view contiguous to the hangers;

Figure 7 is a vertical sectional view of the thrasher adjacent the rear end of the straw rack;

Figure 8 is a sectional view through the operating mechanism;

Figure 9 is a perspective view of a portion of the forward mechanism;

Figure 10 is a sectional view of a portion of the grain pan mechanism;

Figures 11 and 12 are perspective views of 70 the clip;

Figure 13 is a perspective view of the arm;

Figure 14 is a perspective view of the bracket;

Figures 15 and 16 are perspective views of 75 the bell crank lever;

Figure 17 is a sectional view of the tie rods;

Figure 18 is a perspective view of the frame bracket;

Figure 19 is a perspective view of the straw 80 rack plate;

Figure 20 is a perspective view of the hanger for the grain pan;

Figure 21 is a sectional view of a portion of the grain pan hanger;

Figure 22 is a front elevation of the hanger bracket;

Figure 23 is a perspective view of the hanger bracket;

Figure 30 is a side elevation of the arm of the straw rack;

Figure 31 is a side elevation of the frame removed from the thrasher;

Figure 32 is a detail view of one of the 105 corner joints of the frame;

Figure 33 is a sectional view on the line 33—33 of Figure 32;

Figure 34 is a perspective view of the joint;

Figure 35 is a perspective view illustrating the component parts of the joint disconnected.

Referring to the drawings, it will be noted that the invention consists basically of a housing A completely embraced and reinforced in all directions by a specially designed frame B, which in turn exteriorly supports the movable parts and bearings of the novel construction of operating mechanism C, the component parts of which are so compactly associated that the straw rack D and grain pan E have a very compact arrangement so as to function with the other parts of the thrashing machine in a manner to materially lower the center of gravity of the thrasher.

Referring to the drawings more in detail, it will be noted that the housing is of substantially rectangular configuration to provide the top 1, and sides 2 preferably formed from sheet metal so as to not only provide a more substantial construction but to make the same fire-proof. It will be noted by referring to Figures 5 and 6 that the housing is open at the bottom, as indicated at 3.

The frame B is constructed and designed to effectively embrace and be secured to the sides and top of the housing and to extend a predetermined distance below the housing to support various operating structures of the thrasher. This frame B, as illustrated, consists of a pair of upper channel bars 4, 35 one on each side of the thrasher, and a pair of lower channel bars 5, one on each side of the thrasher. These bars are effectively supported in vertical spaced relation and in the proper horizontal plane by the vertical bars 6, that in turn have their upper ends effectively secured together by the cross bars 7 that are parallel and are secured to the top of the housing. As the various bars are riveted to the housing, it will be appreciated that the top and side walls are effectively held against displacement and are capable of fully withstanding the usual strains to which a structure of this character is subject in the use of the thrasher and further to substantially resist any tendency of the movable parts to move out of their proper position.

I wish to call particular attention to the novel manner of forming the joints between the cross bars and the vertical bars which consists in overlapping portions of the vertical bars and cross bars to be bolted together, as indicated at 8, and utilizing a clip 9 for increasing the effective engagement between the bars. To complete the frame, I arrange properly placed braces 10 to materially reinforce the frame.

The operating mechanism C, one of the most important features of the thrashing machine construction now under consideration, is so designed and supported by the

frame that all bearings and the oil cups therefor are exteriorly arranged so as to be readily accessible and to enable the operator to readily view the action of the movable parts.

I will first describe the hanger constructions for properly supporting the straw rack and grain pan for oscillatory movements and then describe the actuating mechanism for giving such oscillatory movements thereto. The grain pan hanger 11 is slightly different in construction from the straw rack hanger 12. Therefore, the two structures will be described separately. The hanger structure 11 comprises a bearing plate 13 bolted so to one of the vertical bars and further provided with a flange 14 for embracing an edge of the vertical bar, and thus this plate is effectively held against dislocation and capable of substantially withstanding all strains to which the same will be subject when in use. This bearing plate 13, which may be in the form of a casting, is provided with ears 15 each provided with an opening 16 for receiving a pin 17. As the pin 17 is movably mounted, the ears form a bearing and, therefore, are provided with oil ducts 18 vertically disposed and readily accessible due to their location. The pin 17 has rigidly secured thereto one end of a link 19, the other end of which loosely receives the protruding end of a bar 20, and as the end is loosely mounted on the bar the same is provided with a vertically arranged oil duct 21 in an accessible position.

At this point I wish to call attention to the fact that although I am describing the supporting construction for one end of the hanger, the construction on the other side of the thrasher is identical. Secured to the grain pan is a pair of brackets 22, one on each side of the grain pan and provided with sockets 23 receiving the bar 20 and secured thereto by the set screws 24, and thus it will be appreciated that the plate and rod are rigidly connected together and as the plates are rigidly connected to the grain pan by the flanges 25 thereof, it will be appreciated that these parts must function properly as they are rigidly connected in their proper associated positions. It will also be appreciated that the construction is such that the grain pan is materially reinforced in a transverse direction and the same is rigidly supported from the frame and thus strains in any direction are properly taken care of.

As will be noted in Figure 2, the straw rack is arranged directly above and in parallel relation with the grain pan and the respective operations of the straw rack and grain pan are such that they may operate in a manner to allow the straw rack and grain pan to be compactly arranged to minimize space for the purpose heretofore set forth.

Referring more particularly to Figure 7,

27, 28, 29 and 30, it will be noted that I provide a second rod 26 for the straw rack hanger which extends in parallelism with rod 20 and is connected to the straw rack and associated parts in a way to substantially reinforce the straw rack in a transverse direction and to transfer the strains of operations of the straw rack to the substantially constructed frame. To accomplish this desired result, a pair of socket members 27 are secured upon opposite sides of the straw rack with their sockets 28 rigidly secured to the rod 26 by the set screws 29. The protruding ends 30 of the rod are rigidly mounted in the socket 31 by the binding action of the set screw 40.

Each arm is of a special construction to function with a clip 33 in a manner to reduce friction and wear to a minimum. To accomplish this desired result, the arm is provided with a cup-shaped hub 34 embracing and enclosing for the proper frictional contact a bearing 35 projecting from the clip 33. A bolt 36 effectively secures the hub to the bearing and is adjustable for compensating for wear. The oil cup 37 is so disposed as to be readily accessible and feeds the oil properly to the contacting surfaces between the bearing 35 and hub 34. The clip 33, which may be a casting, is effectively secured to the upper supporting bar 4 by the bolts 38 and this clip is further provided with a flange 39 engaging the under surface of the bar 4, with the result that the clip is effectively held against displacement and is capable of rigidly resisting the usual strains to which a device of this character is subject.

The actuating or operating mechanism for the straw rack and grain pan as its component parts designed to extend entirely across the straw rack and grain pan and rigidly secured to the upper supporting bars 4, with the result that the forward portions of the straw rack and grain pan are substantially reinforced in a transverse direction and the bars 4 are effectively secured together in a transverse direction at an intermediate point for substantially resisting the usual strains. The mechanism is also designed to have all bearings exteriorly arranged and connected in a novel manner to the power device of the tractor to have all parts readily accessible and visible at all times.

This operating mechanism comprises a support rod 41 extending clear across the thrasher to be rigidly secured on the brackets 42 secured to the bars 4 in a manner to have the protruding ends 43 positioned exteriorly of the housing and frame. On the protruding ends 43 are rockably mounted the bell cranks 44, and to reduce friction to a minimum the hub 45 of the bell crank is provided with a vertically disposed oil cup 46 so positioned as to be readily accessible. As the hub is arranged at the central portion of the bell crank, the arms 47 and 48 of the bell crank

are so disposed as to be operatively associated with other parts of the mechanism, and to accomplish this desired result the arm 47 is provided with a socket 49 provided with a vertically disposed oil cup 50 and loosely receiving the protruding end 51 of a transversely extending straw rack rod 52. This rod 52 is rigidly mounted in the sockets 53 formed on the plates 54 arranged at opposite sides of the straw rack. The plate 54 is of a novel design, as shown in Figure 19, and provided with a vertical flange 55 bolted to the side bar of the straw rack and a horizontal flange 56 secured to the under surface of the side bar.

I wish to call particular attention to the fact that the forward end of the side bar of the straw rack is cut away to snugly receive the flange of the plate 54 and to provide a shoulder 57 abutting the end of the side bar, and thus the plate is very effectively and substantially secured to the side bar so that strains from any direction may be effectively taken care of. The arm 48 of each bell crank is provided with a socket 58 rigidly secured by means of a set screw 59 to the protruding end 60 of the power rod 61. This power rod also extends transversely of the thrasher to position its ends 60 exteriorly of the frame, and as the rod is effectively secured to the bell cranks on opposite sides of the thrasher, it will be understood that this rod 61 performs the dual function of tying the various parts effectively together and to provide power for operating the bell cranks through its connection with the prime mover.

It will also be noted that the rod 61 is positioned below the bottom of the housing to receive the associated ends of the pitmen 62, two in number, and effectively secured to the cranks 63 of the crank shaft 64 that carries the usual pulley 65 for furnishing power to the mechanism. Each pitman at its bearing connection with the rod 61 and crank shaft is provided with an oil cup 66 so disposed as to be readily accessible. It will also be noted that the crank shaft 64 is mounted in bearing elements 67 also connected to certain of the vertical bars, and thus the prime mover is also supported from the frame by bearing elements exteriorly arranged and readily accessible to receive oil in the vertically disposed oil ducts therein.

The grain pan actuating mechanism also consists of a rod 68 of a length to extend clear across the grain pan and frame to have protruding ends 69 exteriorly arranged. This rod 68 is rigidly secured to the hubs 70 of the brackets 71 by the set screws 72. Each bracket is provided with horizontal and vertical flanges 73 that effectively embrace and are secured to the bottom and side bars of the grain pan. Thus it will be appreciated that a rigid connection is established between the two side bars of the grain pan through the medium of the brackets and their rigid con-

nection with the rod 68, thereby materially reinforcing the grain pan in a transverse direction and assuring the proper functioning thereof due to its proper arrangement in place at all times. Clips 74 are rigidly secured to the bars 4 and each is provided with flanges 75 engaging under the bars 4 to cooperate with the rivets or bolts to reinforce the clip against displacement and to withstand the usual strains to which a device of this character is subject. This clip 74 is also provided with a bearing 76 loosely receiving the hub 77 on the arm 78 that is held in place by the bolt 79 that not only holds the hub 77 properly in place but is capable of compensating for wear. The hub 77 is provided with oil cups 80 so disposed as to be readily accessible. The arm 78 is also provided with a socket 81 receiving the protruding end 69 of the rod 68 and rigidly secured thereto by the set screw 82, and thus the grain pan, bracket 71, rod 68, and arm 78 are rigidly secured together as a unit and in their properly related positions.

For the purpose of transmitting motion from the bell cranks, I provide the connecting tie rods 83 having bearings 84 and 85 at their ends provided with vertically disposed oil ducts 86 readily accessible. One bearing 84 is mounted upon the protruding end 69 of the rod 68 and the other bearing engages a pin 87 rigidly carried by its associated bell crank lever.

With the mechanism just described, motion is transmitted in a substantially arcuate manner both to the grain pan and straw rack from a single power rod, which in turn is effectively and substantially operated by pitmen receiving power from the usual crank shaft.

To complete the invention, I arrange the usual blower 88, shaker 89 and conveyor 90 on the lower supporting bar 5, which in turn is supported on the rear wheel structure 91, and thus it will be appreciated that all movable parts and mechanisms are mounted on two sets of superimposed supporting bars, which in turn conjointly are supported upon the rear wheel structure 91, with the upper set of supporting bars further supported by the front wheel structure 92. It will be noted that this front wheel construction 92 includes rearwardly inclined struts 93 connected by clips 94 to an intermediate portion of the upper set of support bars.

Having clearly illustrated and described my invention, it will be fully appreciated that I provide a construction that is rigid throughout and of a design that the various parts are more compactly arranged to materially reduce the center of gravity of the thrasher as a whole. It will also be appreciated that all bearings and oil ducts are exteriorly arranged in positions to be readily accessible and movable parts are visible at all

times so as to readily convey to the operator the relative action of the parts. This is of material advantage in this particular art, as it informs the operator as to the efficient operation of the various parts so when occasion arises minor adjustments may be made readily to assure the operation of the machine at all times with full efficiency.

Upon driving of the pulley 65 by any construction of prime mover, such as a Fordson tractor, the crank shaft 64 will be rotated for reciprocating the pitmen 62, which in turn oscillate the power or support rod 61. As this rod 61 is connected to the lower arms of the bell crank levers on opposite sides of the thrasher, the bell crank levers will be oscillated about the protruding ends of the stationary rod 41. Thus vibratory motion is transmitted to rod 52 by the remaining arms of the bell cranks and by the tie rod 83 to the rod 68. As these rods 52 and 68 are rigidly secured respectively to the straw rack and grain pan, it will be appreciated that these are given reciprocatory and arcuate movements which materially increase the effective action of the straw rack and grain pan upon the material passing thereover.

I wish to call particular attention to the fact that all oil cups or oil ducts are arranged in their most advantageous position to take advantage of gravitational action and to allow ready accessibility thereto, and as the various parts are of a rigid construction assembled together in a rigid manner, it will be understood that the life of the various parts is materially increased, but should occasion arise to renew a part this can be very readily taken care of due to the exterior arrangement of the parts and their mode of connection to associated parts. I wish to further call attention to the rigid manner in which the grain pan and straw rack are supported for relative movement and reinforced in all directions against strain or displacement.

It is, of course, to be understood that the various parts may be designed in other manners than illustrated and associated in other relations and may function somewhat differently from that illustrated and, therefore, I do not desire to be limited in any manner except as defined in the appended claims.

I claim:

1. In a thrasher construction, in combination with the grain pan and straw rack thereof, a frame structure including exteriorly arranged parallel channel bars, rods fixedly secured to the grain pan and straw rack and projecting exteriorly of the thrasher, and operating mechanism therefor bolted to said bars exteriorly of the thrasher.

2. In combination with the straw rack and grain pan of a thrashing machine, rods fixedly secured to the straw rack and grain pan to extend across the same to have their ends

project exteriorly of the thrashing machine, link mechanism connecting the protruding ends of the rods together to be operated in unison, and power means for operating the link mechanism.

3. In combination with the straw rack and grain pan of a thrashing machine, rods fixedly secured to the forward ends of the straw rack and grain pan to extend thereacross and

10 protrude exteriorly of the thrashing machine, operating mechanism operatively connected to all the protruding ends of said rods, and hangers for the rear ends of the straw rack and grain pan including fixedly mounted

15 rods extending across and protruding exteriorly of the thrashing machine.

4. In combination, a frame including horizontally disposed channel bars, a straw rack and grain pan arranged within the frame,

20 hangers supporting the rear end portions of the straw rack and grain pan for vibratory movement, and operating mechanism for the forward ends of the straw rack and grain pan including rods rigidly secured to the straw

25 rack and grain pan to extend thereacross and of a length to have their end portions project beyond the frame to position all bearing surfaces exteriorly of the frame.

5. In combination with a straw rack and

30 grain pan, operating mechanism therefor comprising rods extending across and fixed to the straw rack and grain pan, and operating mechanism for the straw rack and grain pan connected to and movably mounted on said rods.

6. In combination with a frame including horizontally disposed channel bars, a straw rack and grain pan operating mechanism including rods fixed to and extending

40 from one channel bar to the other with their end portions projecting beyond the channel bars, and operating mechanism mounted for swinging movement on the protruding ends of said rods and having operative connection with the straw rack and grain pan.

7. In combination with a straw rack and grain pan, a fixed supporting frame, rods fixedly secured to opposite sides of the frame and extending thereacross and having their

50 end portions projecting exteriorly of the frame, and operating mechanism for the straw rack and grain pan swingly mounted on the protruding end of said rods and including rods fixed to and extending across the straw rack and grain pan.

8. Operating mechanism for a straw rack and grain pan comprising a supporting rod, rods secured to the straw rack and grain pan, and link mechanism swingly mounted on

60 said supporting rod and swingly connected to the remainder of said rods for moving the same.

9. Mechanism for operating a straw rack and grain pan comprising a rod secured to

the straw rack to extend thereacross and have

65 its end portions project beyond the sides of the straw rack, a second rod secured to extend across the grain pan with its ends protruding beyond the sides of the grain pan, a lever connected to the straw rack rod to operate the same, a bracket supporting said lever, operating mechanism for the lever, and a tie rod operatively connecting said lever with the grain pan rod.

10. In combination, a frame consisting of parallel horizontally disposed channel bars and transversely extending bars securing the horizontal channel bars together in proper spaced relation, a grain pan and straw rack mounted within the frame, rods extending

70 across and fixedly secured to said channel bars for supporting the rear ends of the grain pan and straw rack for movement, and operating mechanism for the forward end portions of the straw rack and grain pan and

80 mounted on said transverse bars.

11. A straw rack operating mechanism comprising plates fixedly secured to and embracing an end of the straw rack, a rod extending clear across the straw rack and fixed to said plates, a pivotally supported lever operatively connected to said rod, and power means connected to said lever.

12. Operating mechanism for a straw rack comprising plates fixed to the straw rack, a rod journaled in the plates and rigidly connected thereto, an auxiliary rod, a bell crank lever swingingly mounted on said auxiliary rod and movably mounted on said straw rack rod and giving movements thereto, and power

95 means connected to the bell crank lever.

13. Operating mechanism for a straw rack comprising plates fixed to the straw rack, a rod journaled in the plates and rigidly connected thereto, an auxiliary rod, a bell crank lever swingingly mounted on said auxiliary rod and movably mounted on said straw rack rod and giving movements thereto, power

100 means connected to the bell crank lever, and a grain pan operating mechanism adjustable and operatively connected to said bell crank lever to move in unison with said straw rack rod.

14. A grain pan operating mechanism comprising a rod extending across and rigidly secured to the grain pan, a clip provided with a bearing surface, an arm having one end mounted to move on said bearing surface and having its other end rigidly connected to said rod, power means including a pivotally mounted bell crank lever, and a tie rod operatively and adjustably connecting said rod to said bell crank lever.

15. A grain pan operating mechanism comprising a rod extending across and rigidly secured to the grain pan, a clip provided with a bearing surface, an arm having one end mounted to move on said bearing surface and

having its other end rigidly connected to said rod, power means including a pivotally mounted bell crank lever, and a tie rod operatively and adjustably connecting said rod to said bell crank lever, said tie rod having bearings at its ends movable with relation to the rod and bell crank lever and having its oil ducts vertically disposed.

16. In a grain thrashing machine construction, a housing, a grain pan and straw rack mounted within the housing, a frame secured to and embracing the exterior surface of the housing and including horizontally disposed, exteriorly arranged channel bars, a support rod extending across and rigidly connecting the channel bars together, a rod secured to the straw rack with its ends projecting beyond the housing, a rod secured to the grain pan with its ends projecting beyond the housing, bell crank levers for the ends of the supporting rods, and each having a pair of bearings provided with oil cups and mounted respectively for movement on the supporting rod and on the straw rack rod, clips secured to the said channel bars and provided with bearing surfaces, arms each provided with a hub mounted on the bearing surface of said clip and provided with an oil cup and further rigidly connected to said grain pan rod, a pair of tie rods for the ends of the grain pan rod each having a bearing at one end provided with an oil duct and rotatably mounted on the grain pan rod, a bearing at its other end provided with an oil duct and adjustably connected to said bell crank lever, hangers for the rear ends of the straw rack and grain pan positioned exteriorly and provided with oil ducts arranged in unobstructed position, and power mechanism operatively connected to said bell crank levers.

17. In a grain pan support, a rod fixed to the grain pan, a pair of supporting clips each having a bearing surface, and an arm for each clip fixed to the rod and having a hub

mounted on the bearing surface and having an oil cup.

18. In a grain pan operating mechanism, a rod, a pair of supporting clips each having a bearing surface, an arm for each clip having one end secured to the rod and its other end formed into a hub mounted on the bearing surface and provided with an oil duct, and a bolt securing the arm in engagement with said bearing surface.

19. In combination, a frame, a grain pan and straw rack mounted within the frame, supporting mechanism for the rear of the grain pan, hangers including a pair of fixedly mounted rods extending clear across the rear of the straw rack and grain pan to project exteriorly of said frame, and operating mechanism for the forward end of the grain pan and straw rack including a pair of fixedly mounted rods having their ends projecting exteriorly of said frame to support the operating mechanism.

20. In combination, operating mechanism for a straw rack and grain pan including a forward pair of rods secured to and extending in parallel relation across the forward end of the grain pan and straw rack, and supporting mechanism for the straw rack and grain pan including a rear pair of bars extending in parallel relation across the rear end of the grain pan and straw rack and fixed thereto.

21. In combination, a housing, a frame passing entirely around the housing exteriorly thereof and rigidly secured thereto and including horizontally disposed channel bars arranged flush with the exterior surface of the said housing, and actuating mechanism for the thrasher solely supported by said frame and horizontal bars with all bearings exteriorly arranged.

In testimony whereof I affix my signature.

CHARLES H. TURNER.
